POWER TOOL

Leo F. Kott, Detroit, Mich.

Application January 21, 1946; Serial No. 642,568

5 Claims. (Cl. 255—43)

1

This invention relates generally to power tools and refers more particularly to power tools of the type employed in forming holes in hard substances such, for example, as rock, concrete or similar materials by imparting a succession of blows on the work engaging implement.

One of the objects of this invention is to provide a tool having means for successively moving an implement into engagement with the work to be operated upon at a rapid rate to produce a succession of blows or impacts on the work and having means for rotating the implement during engagement of the latter with the work. Thus, by using an implement in the form of a drill, a combined cutting and pounding action is obtained. This action greatly facilitates forming holes in hard substances of the general type stated and the flutes of the drill or implement enable readily removing the pulverized particles of the substance resulting from the above action.

A further object of this invention is to effectively cool the working parts of the tool by employing means responsive to the rapid motion of the tool on its operative stroke to force a blast of air adjacent the parts of the tool subjected to the greatest heat.

Another object of this invention is to provide a light weight portable tool embodying the above features and composed of a relatively few simple parts capable of being inexpensively manufactured and assembled.

The foregoing as well as other objects will be made more apparent as this description proceeds, especially when considered in connection with the accompanying drawings, wherein:

Figure 1 is a longitudinal sectional view through a power tool embodying the features of this invention;

Figure 2 is a view similar to Figure 1 showing certain of the parts in elevation;

Figure 3 is an end elevational view of the tool;

Figure 4 is a cross sectional view taken substantially on the plane indicated by the line 4—4 of Figure 1;

Figure 5 is a prospective view of a part of the tool shown in Figure 1;

Figure 6 is a fragmentary elevational view, partly in section, of the lower end portion of the tool;

Figure 7 is a fragmentary elevational view, partly in section, of the drive gear embodied in the tool; and

Figure 8 is an enlarged elevational view of a cam follower embodied in the tool.

Referring now more in detail to the drawings,

2

it will be noted that the power tool is provided with a casing 15 comprising two axially aligned sections 16 and 17. The section 16 is threaded into the section 17 and cooperates with the latter to form an enlarged chamber 18 intermediate the ends of the casing. A bevel gear 19 is supported in the chamber 18 for rotation about the axis of the casing 15 and is adapted to mesh with a bevelled pinion 20. The pinion 20 is secured to a drive shaft 21 and the latter is journaled in a projecting portion 22 of the casing section 17 by a ball bearing 23. The projecting portion 22 may form a handle for the tool and the shaft 21 may be connected directly to a suitable prime mover (not shown herein).

The front side of the pinion 19 and the adjacent wall 24 of the chamber 18 are formed with registering annular grooves concentrically arranged with respect to the axis of the casing 15 and adapted to rotatably support a plurality of balls 25. The rear side of the pinion 19 is counterbored to receive an annular ring 26 suitably secured in an annular recess formed in the rear wall 27 of the chamber 18. The adjacent surfaces of the pinion 19 and ring 26 are formed with registering annular grooves for receiving a series of balls 28. The balls 28 cooperate with the balls 25 to provide anti-friction thrust bearings for the pinion 19.

30 A hub 29 is provided at the front side of the pinion 19 and is internally threaded for threadably receiving the rear end of a sleeve 30. The front end of the sleeve is formed with a radially outwardly extending annular enlargement 31 having an annular groove in the periphery for rotatably supporting a series of balls 32. The balls 32 engage the inner surface of the bore 33 formed in the casing section 16 and provide an anti-friction support for the front end of the sleeve 30. An annular seal 34 of resilient material, such for example, as rubber or synthetic rubber, is mounted on the sleeve 30 at the rear side of the enlargement 31 for engagement with the inner surface of the bore 33.

45 An adapter 35 is supported in the bore 33 at the front side of the enlargement 31 on the sleeve 30 and is formed with a radially outwardly extending annular flange intermediate the ends thereof. The flange 36 assumes a position between the enlargement 31 on the sleeve 30 and an annular shoulder 37 formed in the bore 33. The front side of the adapter 35 is formed with a threaded bore 38 for threadably engaging the rear end of a tool holding chuck 39. The chuck 39 has a tapered bore 40 for receiving the corres-

3

pondingly tapered shank 41 of a drill 42. In accordance with conventional practice, the shank 41 is slotted at its rear end and the chuck is reformed with a transverse bore 43 to enable removing the drill from the chuck by inserting a suitable tool into the slotted end of the drill through either end of the bore 43. The rear end of the adapter 35 is formed with a rearwardly extending polygonally shaped projection 44 and this projection is adapted to fit in a correspondingly shaped opening 45 formed in the front end of the sleeve 30. Thus, rotation of the sleeve by the pinion 19 effects a corresponding rotation of the adaptor and tool holding chuck 39.

The rear end of the bore 46 in the casing section 17 is closed by a cap 47 having axially spaced plates 48 and 49. The front plate 49 threadably engages the rear end of the bore 46 and the rear plate 48 is detachably secured to the adjacent end of the section 17 by fastener elements 50. A suitable packing material 51 is confined between the plates and is adapted to engage the inner surface of the bore 46 to prevent the escape of lubricant from the bore. The grip 47 is provided with a threaded bore 52 for threadably engaging a plug 53 and the rear end of the cap is formed with a tubular guide 54.

A plunger 55 is slidably mounted in the casing 15 between the adaptor 35 and the cap 47. The rear end of the plunger telescopically engages the tubular guide 54 and is provided with a radially outwardly extending annular flange 56. The periphery of the flange 56 slidably engages the inner surface of the bore 46 and effectively supports the rear end of the plunger. The front end of the plunger is formed with a radially outwardly extending enlargement 57 and the periphery of this enlargement slidably engages the inner surface of the sleeve 30 to support the front end of the plunger. A coil spring 58 is supported in the casing 15 between the plunger 55 and the plug 53. As shown particularly in Figure 1 of the drawings, the front end portion of the coil spring 58 extends into a bore 59 in the plunger 55 and the rear end of the coil spring abuts the plug 53. If desired, the plug 53 may be provided with a projection 60 which extends axially into the coil spring to stabilize the rear end portion of the latter.

It follows from the above that the plunger 55 is yieldably urged into contact with the adaptor 35 by the coil spring 58. Movement of the plunger by the coil spring 58 is controlled by a cam 61 and a follower 62. In the present instance, the cam extends spirally around the periphery of the plunger 55 intermediate the ends of the latter and is formed integral therewith. The follower 62 is rotatably supported in a radially extending bore 63 formed in the pinion 19 and the radially inner end of the follower engages the cam 61. The plunger 55 is prevented from rotation with the pinion 19 by a pin 64 rotatably supported in a radial bore 65 formed in the casing section 17 and having the inner end engaging in an axially elongated slot 66 formed in the periphery of the plunger 55. Thus, rotation of the pinion 19 relative to the plunger 55 effects a movement of the follower 62 along the cam 61. As shown in Figure 5 of the drawings the cam 61 extends spirally around the plunger for substantially 360°. The angle of the spiral or helix is predetermined so that as the pinion 19 approaches one complete revolution, the plunger 55 is moved to its rearwardmost position against the action of the spring 58. As the pinion 19 con-

tinues to rotate, the follower 62 is disengaged from the high or rearwardmost point 67 of the cam and the spring 58 forcibly moves the plunger forwardly to strike the front end of the plunger against the adaptor 44 with an impact depending to a large extent on the force exerted by the spring. The spring force may be varied by adjusting the plug 53 and the latter is held in its adjusted position by means of a spring clip 68 secured to the cap 47 in frictional engagement with the plug. When the plunger is moved to its forwardmost position by the spring 58, the follower 62 assumes a position adjacent the low or forwardmost point 69 of the cam, so that continued rotation of the pinion retracts the plunger 55 and compresses the spring 58.

The impact or blow applied to the adaptor 35 by the plunger 55 is transmitted directly to the implement or drill 42 and is applied to the work by the drill. At the same time, the drill is rotated by the sleeve 30, so that the work being operated upon is simultaneously subjected to the impact force and to a cutting action. As a result, holes may be readily formed in extremely hard materials such, for example, as rock, concrete and stone.

In order to reduce friction and wear of the parts to a minimum, the follower 62 is rotatably supported in the bore 63. As shown particularly in Figure 8 of the drawings, the follower is formed with axially spaced enlargements 70 having annular grooves in the peripheral surfaces thereof for reciprocably receiving a series of balls 71. The balls 71 engage the inner surface of the bore 63 and provide an anti-friction bearing for the follower. The radially outer end of the follower is formed with a cap 72 seated on a shoulder at the radially outer end of the bore and is provided with a spherical tip 73 which abuts a strip 74. The strip 74 extends across the radially outer end of the bore 63 and is secured to the pinion 19. Thus, the minimum resistance is offered to rotation of the follower 62, and wear of the latter is substantially reduced. The pin 64 is of similar construction and is rotatably supported in a hardened sleeve 74 forming a liner for the bore 65. The pin 64 is held in assembled relationship by means of a plug 75 threaded in the radially outer end of the bore 65.

Upon reference to Figure 2 of the drawings, it will be noted that the chamber 18 communicates with the atmosphere through ports 76 and also communicates with the bore 46 in advance of the enlargement 56 on the plunger through passages 55 77. Thus, air is drawn into and exhausted from the interior of the casing 15 upon reciprocation of the enlargement 56 with the plunger 55. This has a cooling effect on the various parts of the tool and contributes materially to maintaining these parts below critical temperatures. A port 78 is provided in the bore 46 for equalizing the pressure in the bore to the rear of the piston during operation of the tool.

What I claim as my invention is:

1. In a power tool, a tool holder, means for imparting a succession of blows to said holder including a reciprocable plunger, a spring constantly urging said plunger in a direction toward said tool holder, means for intermittently urging the plunger in the opposite direction, said means including a cam on the plunger, a member rotatable about the axis of the plunger, a follower rotatable with said member and engageable with said cam, 70 and a driving connection between the member and

tool holder permitting sliding movement of the latter relative to the former.

2. In a power tool, a tool holder, means for imparting a succession of blows to said holder including a reciprocable plunger, a spring constantly urging said plunger in a direction toward said tool holder, means for intermittently urging the plunger in the opposite direction, said means including a cam on the periphery of the plunger, a member rotatable about the axis of the plunger and having a follower engageable with the cam, means for rotating said member, and a driving connection between the member and tool holder permitting sliding movement of the latter relative to the former.

3. In a power tool, a casing, a plunger mounted for reciprocation within said casing, a gear journaled in the casing and bored to receive the plunger, a cam on the periphery of the plunger extending generally spirally around the axis of the plunger, and a follower rotatably supported in a radial bore in said gear and engageable with said cam.

4. In a power tool, a casing, a tool holder at one end of the casing, a plunger mounted for reciprocation within the casing and having a longitudinally extending groove in the periphery, a pin supported by the casing for rotation and engageable in the groove to hold the plunger against rotation, a spring constantly urging the plunger in a direction toward the tool holder, means for intermittently urging the plunger in the opposite direction, said means including a gear journaled in the casing and bored to receive the plunger, a cam on the periphery of the plunger extending generally spirally around the axis of said plunger, a follower rotatably supported in a radially ex-

tending bore in said gear and engageable with the cam, and means for rotating the gear.

5. In a power tool, a casing, a tool holder at one end of the casing, a plunger mounted for reciprocation within the casing and having a longitudinally extending groove in the periphery, a pin supported by the casing for rotation and engageable in the groove to hold the plunger against rotation, a spring constantly urging the plunger in a direction toward the tool holder, means for intermittently urging the plunger in the opposite direction, said means including a gear journaled in the casing and bored to receive the plunger, a cam on the periphery of the plunger extending generally spirally around the axis of said plunger, a follower rotatably supported in a radially extending bore in said gear and engageable with the cam, means for rotating the gear, and a driving connection between the gear and tool holder permitting sliding movement of the latter relative to the former.
